Primary Examiner — Selina Sikder(74) *Attorney, Agent, or Firm* — Christopher R. Carroll; The Small Patent Law Group LLC(57) **CLAIM**

The ornamental design for an inverter direct current busbar, as shown and described.

DESCRIPTION

FIG. 1 is a perspective view of the inverter direct current busbar;

FIG. 2 is a right side view of the inverter direct current busbar shown in FIG. 1;

FIG. 3 is a left side view of the inverter direct current busbar shown in FIG. 1;

FIG. 4 is a rear view of the inverter direct current busbar shown in FIG. 1;

FIG. 5 is a front view of the inverter direct current busbar shown in FIG. 1;

FIG. 6 is a top view of the inverter direct current busbar shown in FIG. 1; and,

FIG. 7 is a bottom view of the inverter direct current busbar shown in FIG. 1.

The broken lines depict portions of the inverter direct current busbar which form no part of the claimed design.
